UNITED STATES PATENT OFFICE.

JOHN F. ALSIP, OF TACOMA, AND WARD B. ALSIP, OF SEATTLE, WASHINGTON.

CIGAR TRAY.

Application filed July 14, 1919. Serial No. 310,735.

To all whom it may concern:

Be it known that we, JOHN F. ALSIP, a citizen of the United States, residing at Tacoma, in the county of Pierce and State of Washington, and WARD B. ALSIP, a citizen of the United States, residing at Seattle, in the county of King and State of Washington, have invented certain new and useful Improvements in Cigar Trays, of which the following is a specification.

This invention relates to a cigarette tray or ash tray, and the purpose is to provide a simple and convenient form of tray which may be securely attached to a desk or other object. Ash trays of the kind heretofore used have been objectionable, for the reason that they are likely to be tipped over when placed on a desk or table, thus spilling the ashes over papers and other objects. This objection is overcome in the present invention by providing a tray which is adapted to be detachably secured to the edge of a table or desk. A further object of the invention is to provide a cigar tray of simple construction, which may be economically formed of sheet metal, or the like. Still another object of the invention is to provide a tray having one or more depressions to receive and hold cigars in combination with a flexible clasp adapted to engage the under side of the table or desk for holding a tray in position. Other objects relate to various features of construction and arrangement which will appear more fully hereinafter.

The nature of the invention will be understood from the following specification taken in connection with the accompanying drawings, in which one embodiment is illustrated.

In the drawings—

Figure 1 shows a top plan view of our improved tray;

Fig. 2 is a bottom plan view of the same; Fig. 3 is a longitudinal sectional view taken on the line 3—3 of Fig. 1; and

Fig. 4 is a transverse sectional view taken on the line 4—4 of Fig. 1.

The invention comprises a plate 10 of brass or other suitable sheet metal, which is provided with a plurality of longitudinally extending depressions 11 adapted to receive cigars 12. One end of the metal sheet is provided with a rib or crimp 13, and from this rib the sheet metal is reversely bent to form a clasp 15. This clasp

extends downwardly and inwardly in an inclined direction, as shown at 15^a, and is then directed upwardly in an inclined direction, as shown at 15^b, a rib 16 being provided between the two inclined portions 15^a and 15^b. The lateral edges of the inclined portion 15^b converge inwardly, as shown at 17, and this inclined portion terminates in a rounded lip or tongue 18. The middle portion of the clasp 15, adjacent the rib 13, is partially cut away, as shown at 19, and the metal of this portion is bent inwardly to form a lip or flange 20.

The cigar tray thus formed is adapted to be secured to the edge of a table or desk, which is designated in Fig. 3 by the numeral 21. The plate is placed in position over the desk, and the clasp, which is resilient, extends beneath and engages the under side of the top of the desk. When in this position the lip 20 engages the edge of the desk, so that the lower corner of the top of the desk is prevented from engaging the inclined portion 15^a of the clasp, and the tray is thus held securely in position with the under sides of the cigar-holding depressions 11 resting on the upper side of the desk, and with the lip and clasp engaging the edge and the under side of the desk, respectively. When the tray is being passed into engagement with the top of the desk, the inclined tongue 18 engages the lower corner of the top of the desk, and thus causes the clasp to bend downwardly. The tray, after being placed in position, is securely held against movement, and is adapted to hold one or more cigars, which rest therein, as illustrated in Fig. 3 of the drawings.

Although we have shown and described a certain embodiment of the invention for purposes of illustration, it will be understood that it may be constructed in various forms without departing from the scope of the invention as defined in the appended claims.

We claim—

1. In a device of the class described, a cigar tray comprising a sheet metal plate having a depression formed therein, a resilient fastening means formed integrally with said plate whereby said plate may be detachably secured to the top of a table, and an inwardly bent flange formed integrally with said fastening means adapted to engage the edge of said table.

2. In a device of the class described, a cigar tray comprising a sheet metal plate having longitudinal depressions formed therein, said plate being adapted to rest upon the upper surface of a supporting member, and a resilient reversely bent clasp formed integrally with said plate adapted to engage said supporting member beneath said plate.
- 10 3. In a device of the class described, a cigar tray comprising a sheet metal plate having longitudinal depressions therein adapted to hold cigars and rest upon the

upper surface of a supporting member, a resilient reversely bent clasp formed integrally with said plate adapted to engage the lower surface of said supporting member beneath said plate, and an inwardly bent flange formed integrally with said clasp to engage the edge of said supporting member.

In testimony whereof, we have subscribed our names.

JOHN F. ALSIP.
WARD B. ALSIP.
